[57] CLAIM

The ornamental design for a children's wrestling and play enclosure, as shown and described.

DESCRIPTION

FIG. 1 is a perspective view of the preferred embodiment of my children's play enclosure;
FIG. 2 is a front elevation view thereof;
FIG. 3 is a rear elevation view thereof;
FIG. 4 is a right side elevation view thereof, the left side elevation view being identical;
FIG. 5 is a top plan view thereof; and,
FIG. 6 is a bottom view thereof.
